UNITED STATES PATENT OFFICE.

THERON H. TRACY, OF DENVER, COLORADO.

UNIVERSAL COUPLING FOR CONVERTERS.

SPECIFICATION forming part of Letters Patent No. 743,406, dated November 3, 1903.

Application filed January 28, 1903. Serial No. 140,668. (No model.)

To all whom it may concern:

Be it known that I, THERON H. TRACY, a citizen of the United States of America, residing in the city and county of Denver and State 5 of Colorado, have invented certain new and useful Improvements in Universal Couplings for Converters; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 My invention relates to a universal coupling and blast-pipe for converters, my object being to provide a coupling adapted to maintain a tight joint regardless of variations in the position of the converter incident to use; 20 and to this end the invention consists of the features, arrangements, and combinations hereinafter described and claimed, all of which will be fully understood by reference to the accompanying drawings, in which is 25 illustrated an embodiment thereof.

In the drawings, Figure 1 is a side elevation of a copper converter equipped with my improved coupling, which is shown in the open position. Fig. 2 is a vertical section 30 taken through the stand-pipe and coupling, the latter being shown in the closed position. Fig. 3 is a view taken at right angles to Fig. 1, showing the slide-valve and casing in section. Fig. 4 is a detail view of the universal 35 coupling.

The same reference characters indicate the same parts in all the views.

Let the numeral 5 designate a copper converter and 6 the mouth or outer extremity of 40 the conduit connected with the converter and through which the air-blast is introduced thereto. The converter is mounted on wheels 7 and 8 and arranged to turn on a horizontal axis passing through the center of the mouth 45 6 where the air-blast is delivered. The ordinary coupling employed in connecting the blast-pipe with the converter is deficient by reason of the fact that if the position of the converter varies even in a slight degree there 50 will be a binding tendency at the joint and a consequent destructive wear of the parts.

Owing to the heated condition of the converter incident to the treatment of successive charges of molten metal the operating mechanism frequently becomes somewhat disarranged, whereby the axis of the converter is tilted or thrown out of the true horizontal line. My improved coupling is intended to compensate for any changes of position of the character indicated and whereby any 55 binding or unusual wear at the coupling is avoided and a perfectly-tight joint maintained. This function is accomplished by the employment of a universal coupling 9 and suitable mechanism for use in connection therewith, all of which will now be set forth 60 in detail. This coupling 9 is hollow to allow the air-blast to pass into the converter by way of the mouth 6, and its extremities are ball-shaped or constitute spherical segments, 65 as shown at 9^a and 9^b. The extremity 9^a of this coupling when the latter is in the closed position fits a counterpart socket 6^a, formed in the mouth 6, (see Fig. 2,) while its opposite extremity fits a correspondingly-shaped 70 socket 10^a, formed in a piston 10, slideable in a cylindrical chamber consisting of a short branch pipe 12, connected with the main stand-pipe 17. The piston is provided with a cup-leather or suitable packing 14, secured 75 by bolts 15 passing through an interior annular flange of the piston. This cup-leather forms a tight joint between the piston and the interior wall of its chamber. The piston is provided with a central hub 10^c, connected 80 with its body part by spider-arms 10^d. The coupling extremity adjacent the piston is provided with spider-arms 9^d, in which is a semi-spherical socket 10^e, engaged by a ball 15, formed on one extremity of a rod 16, which 85 passes through the hub of the piston, through the stand-pipe 17, and out of said pipe through a stuffing-box 18, its outer extremity being connected at 20 with a hand-lever 19, fulcrumed on a link 22, connected with a lug 90 on the stand-pipe, as shown at 23. The lever 19 is provided with a strap 19^a on one side, forming a guideway to receive an arm 24, pivotally connected with a lug on the stand-pipe, as shown at 25. Mounted on the 95 guide-strap of the lever and threaded therein is a set-screw 26 for locking the lever on 100

the guide-arm in any desired position of adjustment.

The rod 16 is provided with a stop collar or shoulder 16^a. Between this stop and the hub 5 10^c of the piston is located a coil-spring 27. When the parts are in the position shown in Fig. 2, this spring is under tension and holds the piston and coupling tightly seated. The lever 19 is properly adjusted for this purpose. 10 The ball 15 is loose in its socket and shown free therefrom in Fig. 2, indicating that the piston is held in operative relation with the coupling by the tension of the spring 27. When the parts are in the position shown in 15 Fig. 2, it is evident that the converter may have a vertical, tilted, or endwise movement within reasonable limits without interfering in any way with the tight joint connection between the converter and the blast-pipe and 20 without subjecting the parts to undue wear or strain.

The universal coupling 9 may be completely disengaged from the mouth 6 of the converter-conduit by throwing the lever 19 in the direction indicated by the arrow in Fig. 2, whereby the parts are made to occupy the relative position shown in Fig. 1. This is accomplished through the instrumentality of the rod 16, whose ball extremity 15 engages the spider- 25 socket 10^c and forces the piston 10 into its chamber far enough to withdraw the coupling 9 and completely free or detach it from engagement with the conduit 6. This is important when it becomes necessary to remove one 30 converter for repairs or relining and substitute another in its place.

The air-blast is controlled by a slide-valve A, whose stem B is connected with a lever C, acting at right angles to the lever 19. The 40 lever C is fulcrumed on a link D, connected with slide-valve casing, as shown at E. As there is nothing new about these last-named features, further explanation is not deemed necessary. When the coupling is in the closed 45 position, as shown in Fig. 2, the air-blast acts on the piston, which is of greater diameter than the coupling, to hold the engaging coupling parts tightly in contact. The coupling extremities and their engaging parts are 50 ground to form perfect contact with each other.

In the use of converters of the class described it is necessary to change the converter a number of times each day or at stated intervals for repairs or relining. By reason of my 55 improved construction the converter is very quickly and easily detached from or connected with the blast-pipe by the manipulation of the lever 19, whereby the coupling 9 is moved 60 back and forth at will.

Having thus described my invention, what I claim is—

1. The combination with a converter mounted to rotate, and a blast-conduit, of a universal- 65 coupling connection between the converter and the blast-conduit, and means connected with the coupling for disconnecting the latter

from the converter by a longitudinal movement.

2. The combination with a converter mounted to rotate and having an opening in the line of its axis for the introduction of the air-blast, and a blast-pipe, of a ball-joint coupling introduced between the blast-conduit and the converter, and means connected with said coupling for shifting it in the direction of its axis whereby it may be disconnected from the converter. 75

3. The combination with a converter mounted to rotate and having an opening in line with its axis of rotation, and a blast-pipe, of a coupling interposed between the converter and the blast-pipe, said coupling having ball-joint extremities engaging counterpart sockets formed in the connected parts, and means connected with the coupling for shifting the latter sufficiently to disconnect it from the converter. 80 85

4. The combination with a converter mounted to rotate and having an opening for the introduction of the air-blast, said opening being in line with the axis of rotation, and a blast-pipe, of a universal coupling interposed between the blast-pipe and the converter, and a piston located in a portion of the blast-pipe 90 and yieldingly connected with the coupling, the said piston being hollow to permit the passage of the blast, but forming a tight joint exteriorly with its chamber. 95

5. The combination with a rotary converter 100 and a blast-pipe, of a hollow universal coupling interposed between the converter and the blast-pipe and adapted to engage a counterpart socket in the converter-opening, a hollow piston located in a portion of the blast- 105 pipe and having a counterpart socket engaged by the adjacent extremity of the coupling, and a manipulating-rod connecting the piston and coupling, substantially as described.

6. The combination with a converter and a 110 blast-pipe, of a hollow coupling having ball extremities one of which engages a counterpart opening formed in the mouth of the converter-conduit, a hollow piston located in a chamber connected with the blast-pipe and 115 having a central hub suitably connected with its body portion, a manipulating-rod loosely connected with the coupling at one extremity, said rod being provided with a stop, and a coil-spring surrounding the rod and interposed 120 between this stop and the hub of the piston, and means for operating the rod whereby the coupling and piston are given a positive movement in one direction, and a spring-pressure movement in the opposite direction. 125

7. The combination with a converter mounted to rotate and having an opening in the line of its axis for the introduction of the air-blast, of a coupling having one extremity engaging the walls of said opening, the engaging parts 130 being shaped to form a ball-and-socket joint, a blast-pipe provided with a piston-chamber, a hollow piston located in said chamber and forming a ball-and-socket joint with the other

extremity of the coupling, a yielding connection between the piston and the coupling, and means for detaching the coupling from the converter-conduit.

- 5 8. The combination with a converter having an opening to receive the air-blast, and a blast-pipe, of a hollow coupling having ball-shaped ends one of which engages a counterpart socket formed in the blast-mouth of 10 the converter, a chamber connected with the blast-pipe, a piston in said chamber, said piston having a socket fitting the other extremity of the coupling, the piston being movable in its chamber, the air-blast acting to hold 15 the piston tightly against the coupling, a rod loosely connected with the extremity of the coupling adjacent the converter and passing through a hub of the piston, a stop on said rod, a coil-spring surrounding the rod and interposed between the said piston-hub and the 20 stop, and a lever connected with the outer extremity of the rod for manipulating the latter, substantially as described.
9. A conduit for the passage of fluid comprising two parts, and an interposed hollow coupling forming a ball-and-socket joint with one of the parts, a hollow piston located in the other part and having a socket fitting the other ball extremity of the coupling, a rod 25 connecting the coupling and the piston to give the two parts a positive movement in one direction, and a spring interposed between the piston and a stop on the rod for actuating the parts and holding them in opera- 30

tive relation when the rod is moved in the opposite direction.

10. The combination with a converter or similar structure mounted to rotate and having an opening in line with its axis for the introduction of fluid, and a conduit for supplying the fluid, of a coupling having ball-joint extremities one of which engages a counterpart socket formed in the wall of the converter-opening, a hollow piston located in the chamber forming a part of the fluid-supply conduit, said piston having a socket in which the other ball extremity of the coupling fits, the piston being actuated by the fluid-pressure to hold it tightly against the coupling.

11. The combination with a converter or other similar structure mounted to rotate, and a conduit for introducing fluid at the axial center of the converter, of a coupling interposed in the conduit and having ball-joint extremities engaging counterpart sockets, and a hollow piston slideable in one part of the conduit and having a socket fitting one extremity of the coupling, the surface of the piston exposed to the forward action of the fluid being greater than that exposed to the back pressure.

In testimony whereof I affix my signature in presence of two witnesses.
